X-RAY TUBE

Zed J. Atlee, Elmhurst, Ill., assignor to General Electric X-Ray Corporation, Chicago, Ill., a corporation of New York

Application December 7, 1942, Serial No. 468,066

8 Claims. (Cl. 250—144)

The present invention relates in general to electronics and has more particular reference to an improved high frequency electronic tube, the invention relating especially to an X-ray generator.

An important object of the invention is to provide an electronic tube including an anode, a cathode, and a sealed envelope enclosing the same, having enclosed within the envelope transformer means for supplying relatively high operating voltage between the anode and cathode, including facilities for energizing the transformer means from a relatively low voltage energy source outwardly of the envelope.

Another object of the invention is to provide an electronic tube including an anode, a cathode, and a sealed envelope enclosing the same, having enclosed within the envelope oscillator means for supplying operating energy at relatively high frequency between the anode and cathode, including facilities for energizing the oscillator means from a low frequency power source outwardly of the envelope.

Another important object is to provide an electronic tube having transformer and associated oscillator means contained within the envelope of the tube, together with an anode and cooperating cathode whereby all of the high voltage and high frequency elements required to operate the electronic device are contained within the sealed envelope of the tube, only relatively low voltage normal frequency equipment being required outwardly of the tube for the operation of the same.

Still another important object is to provide an electronic tube having means forming an oscillator built into the anode structure of the tube.

A further important object is to provide an electronic tube having transformer means enclosed within the tube envelope wherein a winding of the transformer means is utilized as a support for the anode of the tube.

Another object is to provide an electronic tube having a main anode and cathode enclosed in an envelope, together with an oscillator including a cathode wherein the main cathode and the oscillator cathode comprise filaments energized from a power source outwardly of the envelope through a common conductor extending through a seal formed in a wall of the envelope.

The foregoing and numerous other important objects, advantages, and inherent functions of the invention will be fully understood from the following description, which, taken in connection

with the accompanying drawing, discloses a preferred embodiment of the invention.

Referring to the drawing:

Figure 1 is a diagrammatic illustration of an electronic device embodying the present invention;

Figure 2 is a sectional view taken through a preferred form of device embodying the invention; and

Figures 3 and 4 are sectional views taken substantially and respectively along the lines 3—3 and 4—4 in Figure 2.

To illustrate the invention the drawing shows an electronic device 11 comprising an X-ray generator having an anode 13 forming a target surface 15, and a cathode comprising a head 17 and an electron emitting filament 19, the anode and cathode being enclosed and supported within a sealed envelope 21 formed with an X-ray emitting window 23 opposite the target surface of the anode. Also enclosed and supported within the sealed envelope 21 is a transformer 25 and an oscillator 31, the transformer 25 comprising a primary low voltage winding 27 and a secondary high voltage winding 29. The oscillator comprises a cathode 33 which may be formed as a filament, an anode or plate 35 and a grid 37 disposed between the cathode and the plate for the purpose of controlling electron flow therebetween.

The several elements are interconnected within the envelope, and conductors extending through seals 39 in the envelope walls are provided for electrically connecting the interconnected elements within the envelope with a suitable power source outwardly of the envelope.

To this end the plate 35 of the oscillator may be electrically connected, as by conductor means 41, with the interconnected ends of the transformer windings 27 and 29, the low voltage winding 27 being also connected with a conductor 43 which extends outwardly of the envelope through a seal 39. The high voltage winding 29 of the transformer is electrically connected with the anode 13, as by conductor means 45. The grid 37 of the oscillator is connected to a conductor 47 which extends outwardly of the envelope through a seal 39, and the filaments 19 and 33 are connected in common to conductor means 49 and are individually connected, respectively, to separate conductors 51 and 53. Each of the conductors 49, 51 and 53 extend outwardly of the envelope through suitable seals 39.

Any suitable means may, of course, be employed for supporting the elements within the envelope 21, although, as shown more partic-

ularly in Figure 2, the elements are preferably all supported on a single mounting 55 which forms a sealed closure at one end of the envelope and through which the conductors 47, 49, 51 and 53 extend. As shown, the envelope 21 is of generally cylindrical shape, having a reentrant neck portion 57 at one end, said reentrant portion comprising a glass sleeve forming at its terminal edge a glass-to-metal seal 59 with a short metal sleeve 61, said sleeve, at its end remote from the seal 59, being sealingly secured to the support member 55, which preferably comprises a metal plate sealingly brazed to the short sleeve 61. The envelope 21, including the reentrant portion 57, the sleeve 61 and the plate 55 thus form a sealed enclosure, and the plate 55 forms a support on which the elements of the device are carried. The plate 55 is formed with a plurality of openings 63 therethrough, in which the conductors 47, 49, 51 and 53 are sealingly mounted and preferably insulated from the metal plate 55 by glass globules extending in the openings 63 and forming the conductor seals 39. Within the envelope the mounting 55 preferably carries a cylindrical frame 65 enclosing a space 67 adjacent the inner face of the plate 55. Within the frame 65 the oscillator grid 37 is arranged preferably in the form of a helical coil which is supported on and electrically connected at one end to the conductor 43 which extends through and is supported on the plate 55. Within the helical coil 37 extends a support frame 69, preferably comprising legs of electrical conducting material, the lower ends of which are mounted on insulated supports carried by the plate 55, at least one of which supports extends through the plate to form a part of the conducting means 49. The support frame 69 extends outwardly of the frame 65 within the envelope 21 and carries the cathode 17 in which is mounted the filament 19. One end of the filament 19 is preferably electrically connected to the head 17, and hence through the frame 69 is electrically connected with the conductor 49. The other end of the filament 19 is electrically connected with the conductor means 53 which is insulated from the head 17, as by means of insulating blocks 71, and the conductor 53 extends from the filament within the frame 69 and thence outwardly of the envelope through a seal 39. The oscillator filament 33 preferably comprises a helical coil disposed within the space 67 in position encircling the conductor 53, one end of the filament 33 being electrically connected with the conductor 51 which extends outwardly of the envelope through a seal 39 in the plate 55.

The transformer 25 comprises the primary winding 27 and the secondary winding 29, both of which comprise helical coils disposed one within the other and both encircling the cathode filament and its support. The transformer coils are each mounted at one end on the frame 65 and extend thence in concentric relationship toward the end of the tube remote from the plate 55. The secondary winding 29 extends beyond the winding 27 and substantially to the end of the tube, and is fitted with a preferably metal shell 73 which forms a mounting for the anode 13, which is thus supported on the transformer winding 27 in position opposite the cathode 19. The shell 73 thus forms the electrical connection 45 between the transformer winding 29 and the anode 13.

It will be noted that both windings 27 and 29 of the transformer are commonly connected with

the frame 65 which is of metal and which forms the plate or anode of the oscillator 31. The plate remote end of the transformer winding 27 is connected to the conductor 43 which extends outwardly of the envelope through a seal 39.

After the elements have thus been assembled within the envelope 21, the same may be evacuated and conditioned for service, as by connecting the envelope with an exhaust pump, the connection being sealed off, as at 75, at the conclusion of the tube conditioning period.

Devices embodying the herein described features have the advantage of including in a single envelope all of the frequency and high voltage apparatus required for the operation of the tube at high voltage and frequency. The problems of insulation and protection of high voltage and frequency apparatus outwardly of the tube are thus entirely avoided, since the tube of the present invention may be operated from a low voltage source, which, as shown in Figure 1, may comprise a transformer 77 powered from an energy source, such as a commercial distribution system, at one hundred ten volts and sixty cycles, the transformer 77 being designed to deliver power at, say, one thousand volts for application between the conductors 43 and 49, and to deliver power at lesser voltages between the conductors 49, 51 and 53, the conductors 47 and 51 being electrically interconnected outwardly of the envelope, as by reactive means 79, for the control of the oscillator within the tube.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An electron flow device comprising a sealed envelope, an anode and cathode in said envelope, a transformer and oscillator means comprising an electron source, a plate and a grid within said envelope, said transformer having a primary winding connected with said plate and outwardly of the envelope, and a secondary winding connected between said plate and said anode and supporting said anode, said electron source being connected with said cathode, and means to energize said cathode and said electron source from a power source outwardly of the envelope.

2. An electron flow device comprising a sealed envelope, an anode and cathode in said envelope, transformer and oscillator means within the envelope and operatively connected with the anode and cathode, said oscillator means comprising an electron emitting element, said electron emitting element and said cathode each comprising a filament, said transformer comprising co-axial primary and secondary coils, said secondary coil being arranged to encircle the filament of said cathode, and means comprising a common conductor extending outwardly of said envelope for energizing said filaments for electron emission from power sources outwardly of the envelope.

3. An electron flow device comprising a sealed envelope having a metal envelope portion forming a mounting, means forming an oscillator plate on said mounting, means on and insulated from said mounting and forming an oscillator grid adjacent said plate, an electron emitting fila-

ment on and electrically insulated from said mounting, a cathode on and insulated from said mounting, an anode, and means forming a transformer winding supported on said mounting and in turn supporting said anode in operative position with respect to said cathode.

4. An X-ray generator comprising a sealed envelope having a metal envelope portion forming a mounting, means forming an oscillator plate on said mounting, means on and insulated from said mounting and forming an oscillator grid adjacent said plate, an electron emitting filament on and electrically insulated from said mounting, an anode forming an X-ray generating target, a cathode on and insulated from said mounting in position to deliver electrons on said target, and means forming a transformer comprising windings electrically connected on said oscillator plate, one of said windings carrying said anode and the other having a connection extending outwardly of said sealed envelope.

5. An X-ray generator comprising a sealed envelope having a metal envelope portion forming a mounting, means forming an oscillator plate on said mounting, means on and insulated from said mounting and forming an oscillator grid adjacent said plate, an electron emitting element on and electrically insulated from said mounting, an anode forming an X-ray generating target, a cathode insulated from said mounting in position to deliver electrons on said target, and means forming a transformer comprising windings electrically connected on said oscillator plate, one of said windings carrying

said anode and the other having a connection extending outwardly of said sealed envelope.

6. An electron flow device comprising a sealed envelope, an anode and opposed cathode in said envelope, a transformer and oscillator means within the envelope and electrically connected with the anode and cathode, said oscillator means comprising a plate member, said transformer comprising a winding supported on said plate member and in turn carrying said anode in opposing relation with respect to said cathode.

7. An electron flow device comprising a sealed envelope, an anode and opposed cathode in said envelope, oscillator means within the envelope and electrically connected with the anode and cathode, said oscillator means comprising a shell member forming an oscillator plate, an oscillator grid and electron emitting means enclosed within said shell member, said anode being supported on said shell member in opposing relation with respect to said cathode.

8. An electron flow device comprising a sealed envelope, an anode and opposed cathode in said envelope, transformer means and oscillator means within the envelope and electrically connected with the anode and cathode, said oscillator means comprising a shell member forming an oscillator plate, an oscillator grid and electron emitting means enclosed within said shell member, said transformer means comprising a winding supported on said shell member, said anode being supported on said winding in opposing relation with respect to said cathode.
